FIG. 10

FIGURE 1 is a side elevational view of a tractor shovel, showing our new design;

FIGURE 2 is a front perspective view thereof;

FIGURE 3 is a front elevational view thereof;

FIGURE 4 is a rear elevational view thereof;

FIGURE 5 is a rear perspective view thereof;

FIGURE 6 is a side elevational view of a modified form of the tractor shovel of FIGURE 1;

FIGURE 7 is a front perspective view thereof;

FIGURE 8 is a front elevational view thereof;

FIGURE 9 is a rear elevational view thereof;

FIGURE 10 is a rear perspective view thereof.

The essential features of our design reside in the portions illustrated in solid lines.

The sides not shown are mirror images of the sides shown in FIGURES 1 and 6.

This is a continuation of application Serial No. D. 66,404, filed August 18, 1961, and of application Serial No. D. 66,415, filed August 18, 1961, both now abandoned.

We claim:

The ornamental design for a tractor shovel, as shown and described.
